UNITED STATES PATENT OFFICE.

CHARLES D. SEEBERGER, OF NEW YORK, N. Y., ASSIGNOR TO OTIS ELEVATOR COMPANY,
A CORPORATION OF NEW JERSEY.

CONVEYER.

994,879.

Specification of Letters Patent. Patented June 13, 1911.

Application filed October 22, 1901. Serial No. 79,520.

To all whom it may concern:

Be it known that I, CHARLES D. SEEBERGER, a citizen of the United States, residing at New York, in the county of New York and State of New York, have invented certain new and useful Improvements in Conveyers, of which the following is a specification.

My invention is concerned with certain new and useful improvements in that class 10 of conveyers which are intended to transport passengers or freight from one floor or level to another by means of a continuously moving support upon which the load rests and by which it is carried up or down 15 as the case may be, and it relates in its specific application to improvements in moving stairways, and is adapted to insure their perfect operation without any possibility of 20 accident to the mechanism or to the load.

One feature of my invention is concerned 25 with a driving mechanism, such as a sprocket wheel, meshing with both the ascending and descending portions of the chain connecting the series of steps or carriers, to relieve the strain at the curved portions of the path or way, such as the transition from incline to horizontal and at the 30 end-carriage or reverser, and to balance the weights of the ascending and descending parts on the incline; the sprocket-wheel being preferably located at a point near the curve connecting the inclined and upper horizontal runs, but at a distance from the 35 curve permitting a straight tangential run of at least one link length.

Another feature of my invention is found 40 in the location of the driving mechanism, such as a sprocket wheel, as near the top of the incline as possible to haul the steps up the incline without throwing any of their weight on the curves of the track, and so that the drive will carry the weight or load of the connected series of steps which otherwise 45 would be taken by each step at the time it passes from the incline to the upper horizontal run.

Another feature of my invention is found 50 in the construction of the links, which are of a special design that takes all the strain off the axles of the trucks, and also permits the removal of any axle for any purpose, without breaking the continuity of the chain.

Another feature of my invention is found 55 in the suspension of the supports carrying

the end or reversing portions of the tracks so as to accommodate automatically the lengthening or shortening of the chain due to the varying positions of the links or that 60 may take place under changes of temperature or otherwise so as to keep it in proper adjustment under all circumstances.

Another feature of my invention is the employment of mechanism by which the 65 synchronism of movement of the hand rail and the steps is called to the attention of the passenger by means of appealing to his sense of seeing, hearing and feeling.

Another feature of my invention is con- 70 cerned with a brake mechanism which I employ to prevent the possibility of the mechanism turning backward and causing an accident in case of breakage.

Other features of my invention will be 75 fully described and particularly pointed out in the claims.

Referring now to the accompanying sheets of drawings, in which the same reference characters are used to designate identical parts in all the figures, Figure 1 is a central section through the lower portion of the stairway with some of the trucks omitted to more clearly disclose the parts in connection therewith; Fig. 2 is a similar view of 85 the upper end of the stairway, but with the chain entirely omitted and the positions of the axles of the trucks indicated; Figs. 3, 4 and 5 are detail views in side elevation, plan and cross section showing how the tracks are 90 telescoped from the stationary parts to the movable end-carriages or reversers; Fig. 6 is a detail view of the upper driving pulley for one side of the moving hand rail; Figs. 7 and 8 are detail views in side and end ele- 95 vation showing the adjustable tracks upon which the end-carriages are supported; Fig. 9 is a plan view of one of said adjustable tracks; Fig. 10 is a plan view of a portion of the upper landing, and with a portion of the stairway beneath it in section on the broken line A—A of Fig. 2; Fig. 11 is a similar view of the lower end of the stairway in section on the broken line B—B of Fig. 1; Figs. 12, 13 and 14 are a sectional 100 view, side elevation, and plan view, respectively, illustrating the construction of the links of the driving chain; Fig. 15 is an elevation in section on the line C—C of Fig. 2, but on a larger scale, and with the connecting sleeve omitted; Fig. 16 is a similar 110 view in section on the line D—D of Fig. 1;

Fig. 17 is a sectional view showing the details of the mechanism for driving the moving handrail, with the relative position of the steps thereon indicated to show how 5 the synchronism of the movement of the steps and the handrail is forced upon the attention of the passenger; Fig. 18 is a sectional view through the balustrade on the line E—E of Fig. 17; Fig. 19 is a sectional 10 view through the hand-rail on an enlarged scale; Fig. 20 is a rear elevation of the preferred form of the truck and step supports, with the riser omitted; Fig. 21 is a section 15 on the line F—F of Fig. 20, and Fig. 22 is a partially diagrammatic view showing the 20 stationary balustrade (with the lower member or curtain omitted) and the steps in horizontal portions of the return line illustrating the overlapping of their tread surfaces upon the concave curve or when viewed 25 from beneath.

Referring to Figs. 1 and 2 the moving 25 stairway is made up of a connected series of steps which travel on ways providing ascending and descending inclined runs having horizontal end portions to form landings, in the present instance arranged in 30 upper and lower relation, and also having end-carriages or reversers. Upon the transporting portion of the inclined run the steps are in step-like formation, while upon the horizontal end portions their treads are 35 in the same horizontal planes for sufficient distances to present plane-surfaced entrance and exit landing portions. Each step 20 is mounted on a step-frame having a truck or wheel-base composed of opposite 40 side-bars 21 and 22, each of which has a front-wheel 23 and a rear wheel 24. The side-bars are offset at their centers as shown in Fig. 10, so that the front wheels 23 are in different vertical planes from, and a 45 sufficient distance inside of, the rear wheels to permit adjacent trucks to overlap each other. The side bars are connected by axles or bolster rods 25. In the form shown in 50 Fig. 10, each axle has brackets 26 secured to its outer ends just inside the side bars, the brackets being preferably pinned to the axles and the tread portion 27 of the steps and their associated risers 28 are secured to 55 these brackets in any desired manner. These step-units are connected in an endless 60 series or chain, the axles 25 of the various trucks being connected by the rack-links 29, which are best shown in detail in Figs. 12 to 14, and consist of the male and female 65 links, each link having the side bars 30 connected by the pins or rods 31, which constitute the rack teeth, the male link having at the ends of the side bars 30 the sleeves 32, through which the axles 25 pass, and which 70 in turn fit in the encircling sleeves 33 ter-

minating the ends of the side bars of the female links. This construction enables the links to swing freely upon each other, as is necessary to pass from the inclined to the horizontal portions of the stairway and to 75 turn around the end-carriages or reversers. This construction forms a larger frictional bearing surface than would be possible if the ends of the links were both pivoted on the axle 25, and what is of still greater importance, the strain resulting from the weight of the annexed step units is transmitted from one link to another, and does not tend to bind on the axles or to shear them off, as would be the case with the ordinary construction. This construction also 80 enables me, if occasion arises, to remove any of the axles 25 without dismantling or disconnecting the chain, as would be the case if the ordinary construction were employed. The wheel-base is broader than the tread, whereby stability is assured and accidental tilting is prevented, the center of 85 gravity of the step and its load being at all times within the area of the wheel-base. 90 The center line through the wheel-base is parallel with the tread, whereby the wheels may run on tracks at the same level on horizontal portions of the way but at different levels on the inclined transporting 95 portion, the tracks being in parallel oblique planes on the latter and in the same horizontal planes on the former. The forward wheels 23 run on the tracks 34, which reference character I apply to the stationary or fixed portion of the complete tracks 100 covering the entire circuit. The tracks 34 project farther forward into the body of the machine than do the similar tracks 35 upon which the rear wheels 24 run. As seen in 105 Fig. 1, on the ascending incline, the tracks 34 are a sufficient distance below the tracks 35 so that the steps while running on these tracks will still retain their treads in horizontal position. On the descending incline 110 the tracks are on the same level so that the treads of the steps are inclined at the same angle as the tracks, as clearly shown in Fig. 1. The tracks 34 and 35 on the inclined 115 portions are supported by any suitable means, such as the plate girders 36, which in turn are supported in any suitable manner upon the floors of the building or other structure in which the machine is located.

To drive the chain, I preferably employ 120 an electric motor 37 located in the position indicated in dotted lines in Fig. 2, which has its armature shaft 38 provided with the two oppositely directed worms 39 which mesh 125 with the two oppositely rotating worm wheels 40, which mesh with each other, and one of which meshes with a spur wheel (not shown) secured on the same shaft as the lantern pinion 41, which is mounted in a suitable support 42, and which in turn 130

meshes with the driving gear wheel 43, the shaft of which is mounted in suitable bearings 44 carried by the plate girders 36 or other suitable supporting means. This arrangement of the armature shaft with the two oppositely disposed worms and gear wheels meshing with each other serves to neutralize any thrust that may be given to the armature shaft and causes the mechanism to run more steadily and with less friction and wear than it would otherwise. It will be seen that the driving mechanism, including the motor, is contained within the body of the machine and does not require space outside. It is of course understood that the drive wheel may be operated in any suitable manner from any suitable source of power. The driving gear wheel 43 is, as seen in Fig. 2, located as near the upper end of the inclined portion as possible so as to engage the ascending line of links on the incline or below the change of direction in passing to the curve between the inclined and upper horizontal portions of the way, and to engage the descending line of links above the change of direction at a point where it extends in a tangential run after it has started to leave the horizontal run and before it enters the inclined run as herein-described, and the drive is arranged so as to mesh with the axles 25 and the pins 31 of both the ascending and descending adjacent portions of the chain at points where the lines of the chain are not parallel. By having the driving gear meshing with the ascending and descending portions of the chain, I practically divide the weight of the moving parts on the driving gear into two parts so that the entire weight is not thrown on the few driving teeth with which the chain engages on one side only, but is thrown upon the driving teeth on both sides of the wheel, thereby engaging with twice as many teeth and thus lessening the strain on each tooth and its possibility of breakage. This construction also divides the slack in the chain between the portions above and below the driving gear, this provision for the slack being of special importance in connection with the employment of the movable end-carriages or reversers to be described hereafter, as it is apparent that if the drive did not engage the return run, the entire weight of the descending line or run would be borne by the end-carriage and on the curve, and moreover the weight or drag of the descending line would fall on the middle of the axles whose ends bear the tracks at the curve and would strain and distort the step units. Furthermore, as both runs engage the drive wheel, the weight or drag of the descending line tends to counterbalance the weight or pull of the ascending run, the entire machine being thus counterbalanced through the drive. Also, by locating the drive where it engages the steps before they pass to the curves, the strain or weight of the moving parts is taken off the curves, around and over which they would otherwise be pulled or dragged, and strain or tension is established in the chain on the incline. In the actual embodiment of my invention I have so located the drive that it engages the links of the ascending portion before they pass to their curve and the links of the descending portion in the tangential run introduced in the curve, so that the weight of both depending lines hangs on the drive and the strain or weight is taken off the curves of both runs. It will be apparent that I may produce substantially the same effect with regard to dividing the strain on the teeth and also the slack in the chain by employing a driving pinion meshing with both lines or meshing with only one line of the chain and by employing in addition thereto a pinion, such as 45, indicated in dotted lines in Fig. 2, and which is merely an idle pinion and is not connected with the driving pinion, but which meshes with both lines of the chain, and may be located at any suitable point in the incline. By this arrangement the weight of the steps down the incline is on the idler; when the machine is at rest there is practically no pressure on the teeth of the driving pinion, and when it is in motion the drive takes only the pressure due to friction in the conveyer, to driving the hand rails and shunt, and to the live load. I make no specific claim in this application to an arrangement of the parts where the drive meshes with one line and the idler with both lines, but expressly reserve the same as part of the subject matter of my co-pending application filed October 18, 1905, Serial No. 283,302, and I make no claim in this application to means for reducing or establishing tension or strain in the chain of steps at certain points, except as the driving wheel itself produces such function, but hereby expressly reserve the same for my co-pending application filed November 24th, 1902, Serial No. 132,513. When the drive and idler mesh with both lines as shown in Fig. 2, the idler relieves the drive of that part of the load or weight of both lines below the idler, thereby dividing the weight.

At the upper end of the stairway, for the portion constituting the landing, the tracks 34 and 35, which were on different inclined planes, come together in the same horizontal plane, so that the tracks on the landing portion run horizontally so as to have one or more of the tread surfaces of the steps constitute a substantially continuous horizontal surface of varying length according as the landing is long enough to include one or a plurality of steps. The loops or curved tracks 46 and 47, constituting the continuation of the tracks 34, and the loops or

curved portions 48 and 49, constituting a continuation of the tracks 35, and by which the direction of travel of the steps is reversed, are carried by the end-carriage or 5 reverser 50, which consists of the side pieces 51, which may be connected together by any suitable means, such as the cylindrical sleeve 52 to the flanged ends of which the plates 51 are bolted. The end-carriage 50 is supported by means of the bearing flanges 53 and 54, which rest on the anti-friction rollers 55 and 56, which in turn rest upon the tracks 57 and 58, which, as shown in Figs. 7 10 to 9, have inclined under surfaces or faces 15 resting upon the oppositely inclined upper surfaces or faces of the wedge-shaped supports 59 and 60, so that by moving the tracks 57 and 58 longitudinally, the end carriage 50 may be raised and lowered as much as 20 may be necessary to bring the overlapping portions of the tracks 46 and 48 exactly in line with the overlapping portions of the tracks 34 and 35 on the upper side, and the overlapping portions of the tracks 47 and 25 49 into register with the corresponding portions of the return tracks 34 and 35. The upper end-carriage should be normally supported in outward or rearward position so as to take up as much slack as there may be 30 in the chain above the driving wheel 43, and for this purpose I employ any suitable means. In the form shown I provide one or more weights 61, which are connected by cords or chains 62 to the end-carriage 50 and 35 pass over sheaves 63 suitably supported on the main frame work 64 at the upper end of the stairway so that the tendency of the weight 61 is to keep the end-carriage drawn out or in a position as far to the rear as the 40 tension of the chain will permit. At the lower end is a similar construction, as I employ the end-carriage 65 consisting of the side plates 66 which are connected by the cylindrical flanged sleeve 67 to which they are 45 bolted at either end in the same manner as the other end-carriage 50. These side plates carry the loops or curved tracks 68 and 69, which form the continuation of the track 34, and the loops or curved tracks 70 and 71, 50 which form a continuation of the tracks 35, and by which the direction of travel of the steps is reversed. The end-carriage 65 is supported by means of the flanges 72 and 73 as shown in dotted lines in Fig. 1, which 55 rest upon anti-friction rollers 74 which in turn rest on the adjustable blocks 75 having the inclined under surfaces or faces which can be moved on the correspondingly inclined upper faces of the blocks 76 which are 60 supported in any suitable manner, as on the flanges 77. By means of these blocks 75 and 76, the end-carriage 65 can be raised or lowered as much as may be desired to cause the overlapping portions of the tracks 70 65 and 71, and 68 and 69, to register with the

coöperating portions of the tracks 35 and 34 respectively. The lower end carriage should be normally in position to produce slack in the ascending portion of the chain between the lower landing and the driving sprocket so that the steps will not be lifted off of the tracks by reason of the angle formed when they pass from the horizontal to the incline, and for this purpose any suitable means may be employed. In the form 70 shown, I employ on one or both sides the weights 78 which are suspended by the cords 79 from the bell crank lever 80 which is pivoted at 81 to some suitable portion of the stationary support, and has pivoted at its 75 upper end the link 82, which in turn is pivoted to the side plate 66, this construction causing the weights 78 to hold the end-carriage 65 normally in a forward position to produce the slack in the chain. The upper 80 and lower end-carriages are thus respectively weighted out and weighted in, so that the necessary slack in the chain is provided below the drive to prevent the steps from being lifted off the tracks, and the necessary 85 strain in the chain is provided above the drive to prevent them from buckling up. The end-carriages thus provide means for regulating the tension on the chain passing through the curves. Also, by means of the 90 floating end-carriages the track length always corresponds to the length of the step-linkage, adjusting itself automatically thereto. As the end-carriages are yieldingly supported, provision is made for accommodat- 95 ing any unusual conditions. 100

In Figs. 3, 4 and 5 I have illustrated one way in which the stationary parts of the tracks 34 and 35 may be telescoped with the movable parts, as 68 and 70, for example. The tracks 68 and 70 are brought together on a level and they are cut away at their adjacent edges to form the enlarged recess into which fits the reduced ends of the tracks 34 and 35. In Fig. 5 the position of the wheels is indicated in dotted lines showing how their peripheries extend over the overlapping portions of both sections so that they are supported whether resting on either or both sections. This or any equivalent arrangement is duplicated at all necessary points. The tracks form a continuous support for the steps throughout the circuit of their travel. The curves between the incline and the end portions or horizontal landings are made or compounded so as to provide constant speed, and the curves in the end-carriages are similarly arranged, so that trackage providing constant speed and embracing all curves, end-carriages and other 110 portions of the circuit is provided. It will thus be seen that I have provided a system in which the steps are continuously supported by tracks at all parts of their travel, and also provided a path for the wheels at all 115 120 125 130

times exactly corresponding with the length of the chain.

To supply a support for the hands of the passengers as they are using the machine, I preferably employ a moving hand-rail, such as is illustrated in Figs. 1, 2, and 15 to 19, which runs upward parallel with the line of movement of the treads at a suitable height therefrom, and returns on the under-
10 side, forming a continuous belt. The hand-rail and its mechanism may be duplicated on each side of the machine, so a description of one will suffice. At the lower end, I place on one or both sides a hollow newel post 83, which has journaled therein the driving sheave 84, which is connected by the shaft 85 mounted in the bearing 86 with the driving pulley 87. This pulley is driven by means of a gear wheel 88 secured on the 20 shaft 89 extending between the side supports in a position where it meshes with links of the driving chain, preferably with the under side thereof, as shown in Fig. 1. As the stairway runs, the shaft 89 will be 25 rotated and it has secured on the outer ends thereof the pulley wheels 90, each of which is provided with a rope or cable 91 passing around a pair of tightening pulleys 92 thence around a sheave 93 and around the 30 pulley wheel 87, thence to sheave 94, and thence back to the pulley 90, so that as the stairway runs, the sheaves 87, 93 and 94 will be rotated at a peripheral speed corresponding to the rate of movement of the stairway 35 so that the flexible hand-rail 95, which passes over the driving sheave 84 will move synchronously with the steps. At the upper landing, I provide a similar newel post 96, which has journaled therein the hand-rail 40 driving sheave 97, secured upon the shaft 98 which passes through the bearing sleeve 99 and has secured to its outer end the driving pulley 100. The shaft 101, upon which the driving gear wheel 43 is mounted, has at its 45 outer ends the pulley wheels 102, and a rope or cable 103 passing around the pulley wheels 100 and 102 and beneath the belt tightener 104 serves to rotate the driving wheel 97 at the same peripheral speed as the 50 driving wheel 84 at the bottom landing. The upper driving sheave 97 practically serves to pull up so much of the ascending portion of the hand-rail as is on the incline, but no more, as the horizontal portion is 55 pushed forward by the lower driving sheave 84.

To increase the adhesion of the hand-rail 95 upon the driving sheave 84, so that it will produce the necessary slack in the horizontal 60 available portion of the hand-rail at the lower landing which serves to prevent the binding of the rail upon its support or the tendency of the rail to lift off its support at the curve between the horizontal and inclined ascending portions which the pull of

the sheave 97 tends to produce, I employ the auxiliary driving pulleys 105 and 106, which are mounted on the shafts 107 and 108 journaled in suitable bearings 109 and 110 carried by the standard 111 which supports the bearing 85 for the wheels 84 and 87. These shafts 107 and 108 have the pulley wheels 94 and 93, previously referred to, secured on their outer ends. A belt 112 connecting the driving pulleys 105 and 106 co-operates with 70 the outer surface of the hand-rail 95 so as to hold it securely against the driving wheel 84, and thus aids in driving the hand-rail positively so as to prevent any possible slipping thereof over the pulley. To adjust the various parts of this hand-rail driving mechanism so as to take up any slack that might occur in the hand-rail, the standard 111 can be adjusted longitudinally of the support 75 113 to which it is secured by means of the set screw 114, which operates in the customary manner for this class of devices. To regulate the position of the wheels 105 and 106, they are respectively mounted upon supports 115 and 116, which, as shown in 80 Fig. 17, are adjustable vertically and horizontally respectively by means of the set screws 117 and 118 so that any desired pressure or adhesion upon the belt 112 relative to the hand-rail can be applied. The hand-rail in its upward movement travels on the stationary rail or guide 119, shown in section in Fig. 18, which may be mounted on the upper edge of the balustrade, and which is undercut, as shown, so that the inturned 85 edges of the hand-rail 95 grip on it to prevent the hand-rail being lifted off of it either willfully or accidentally. To retain this hand-rail in the necessary shape to grip on the rail 119, I may place at intervals in 90 the rubber and fabric of which it is preferably composed, a similarly shaped strip of steel or some other suitable rigid substance, as indicated in dotted lines at 120 in Fig. 19. It will thus be seen that the hand-rail is 95 practically a homogeneous unit driven by frictional contact with the driving wheel without the intervention of a chain or teeth, and of such design that the hand rail can pass around the wheels or curves located in 100 any plane. The hand-rail 95 after ascending and passing around the wheel 97 at the upper end descends parallel to its ascent in the channel 121 formed in the bottom of the balustrade, a special track 122 being preferably employed for the hand-rail to travel over, as shown in Fig. 18. To assist in guiding the hand-rail in the proper position on its return, I employ the sheave 123, which as 105 shown, is journaled at a suitable point within the hollow newel post or horizontal portion of the balustrade.

To indicate to the user the synchronism of movement between the steps and the hand-rail, I may paint or otherwise decorate 110 130

the alternate sections 124 thereof, which are of the same length as the width of the tread surface of a step, so that the boundaries of the spaces 124 and the steps will be the same, 5 so that when the passenger is on one step, his hand will naturally rest upon the corresponding space 124 of the hand-rail, thus synchronizing the motion of the two by appealing to his sight. To appeal to his sense 10 of feeling, I provide, as shown in Fig. 17, the landing 125 with a flexible mat 126, which extends over the treads or a portion thereof so that as the user steps on the mat 126 he will feel the treads coming into their 15 horizontal position, and thus the rhythm of the movement will be felt by him at the same time that the spaces 124 emerge from the newel post. I may further indicate this audibly by employing a bell 127 mounted on 20 the interior of the newel post and having the hammer 128 thereof in position to be struck by the pins 129 on the driving wheel 84, these pins being spaced apart so that each time the bell is sounded the hand-rail and treads will 25 have advanced a distance equal to the length of one step.

To indicate to and compel the user to leave the stairway at the upper landing, I provide the shunt mechanism 130 shown in 30 Figs. 2, 10 and 15, which is an improvement on that shown in my Patent No. 617,779. As will be seen, I also mount on the shaft 101 the pulley wheel 131, around which travels a rope or cable 132, which, after 35 passing over the pair of tightener wheels 133, suitably mounted, passes over the sheave 134 secured on the shaft 135 mounted in the supports near their upper end. Secured on the same shaft adjacent to this 40 pulley wheel 134 is the pulley wheel 136, which carries the rope or cable 137, which passes over the vertical sheave 138 and the inclined sheave 139 which are so located and mounted as to properly direct the rope 137 around the 45 horizontal sheave 140, which is secured to the lower end of the vertical shaft 141 which is journaled in suitable bearings in the supporting frame of the shunt mechanism 130. At the upper end of the shaft 141 is an 50 other sheave 142. Parallel to the shaft 141 and similarly located on the other side of the landing is the shaft 143, which has the sheave 144 on its upper end in the same horizontal plane as the sheave 142. A 55 crossed rope or cable 145 is passed over the sheaves 142 and 144 so that the shafts 141 and 143 rotate synchronously but in opposite directions. The shafts 141 and 143 have secured thereon beneath their respective 60 sheaves 142 and 144, the belt pulleys 146 and 147. Mounted between these shafts 141 and 143, and in advance thereof, are the shafts 148 and 149, which have the belt 65 wheels 150 and 151, respectively, secured thereon in the same horizontal plane as the

belt wheels 146 and 147 and at or near the center of the steps. A pair of heavy leather or rubber belts 152 and 153, respectively, are mounted on the belt pulleys 146 and 150, and 147 and 151, respectively, and it will be seen that as the machine is running, the belts 152 and 153 will travel from the center toward the ends of the treads. These belts fit down as close as may be to the 70 surfaces of the treads of the steps, which in this position are horizontal, and the frame work 154, in which the shafts 141, 143, 148 and 149, and their associated parts, are mounted, is covered by a box-like casing 155, shown in position and in section in Fig. 2, 75 which extends down on the front side to the upper edge of the belts 152 and 153. With this construction, if any passenger neglects to step off of the upper landing, when he reaches the shunt, the belt 152 or 80 153, as the case may be, will force him off of the treads, and the belts are set down so closely to the tread surfaces of the steps that it is impossible for the foot or any portion of one's clothing or other object to be caught 85 thereby. The belts 152 and 153 are geared to run at a lineal speed so much greater than that of the steps, that their forward component of movement, (of which, together with the movement at right angles thereto, the 90 diagonal movement may be considered a resultant) in the direction of the movement of the steps is at least equal to the rate of movement of the steps, so that a person or object remaining on a step, will, when he reaches the shunt, be forced along the length of the step and directly off of it, instead of 95 backward upon the succeeding step, as would occur if it ran slower than the minimum relative rate specified. In other words, the belt speed is enough greater than the step speed so that the resultant of the two speeds produces motion at an angle, preferably a right angle, to the direction of 100 travel of the steps. It is apparent that this principle of operation might be applied to 105 conveyers of any kind.

To prevent the possibility of any accident by reason of the steps running backward, in case the stairway should be crowded and the driving machinery should be suddenly stopped or become disabled, in which case the weight of the passengers or freight would tend to run it backward, I employ 110 the brake mechanism illustrated in Figs. 2 and 15, where it will be seen that I surround the shaft 101 by a collar 156, which is suitably supported from one of the side pieces 115 156 by means of the brackets 157. This collar 156 has formed therein the eccentric recesses 158 (shown in dotted lines in Fig. 2), in which are placed clutch rollers 159. These eccentric recesses 158 are of a sufficient width at one end to permit one or more rollers 159 to roll freely therein as the driv- 120 125 130

ing shaft 101 rotates in one direction, but if the direction of rotation of the driving shaft should be changed, the friction of the shaft on the rollers will force them into the narrower portions of their recesses so that they will be jammed between the shaft and the edges of the recess so as to stop the shaft 101 from any further rotation. Of course it will be understood that any other sort of 10 a clutch mechanism might be employed.

Another feature of my invention consists in the shape given to the steps whereby it is possible for them to overlap slightly as is necessitated in the concave curve seen at the 15 lower side of Fig. 22, where the positions the steps assume are clearly shown, and where it will be seen that the treads pass through a circle or curve of a smaller radius than do the link centers or axles of the 20 trucks, instead of through one of a larger radius as occurs on the convex curves. To permit this, the thickness of the forward edge of the step is reduced, as shown at 160 in Fig. 22. A convenient method of making 25 this construction is to support on the brackets 26 the hollow rectangular frame 161, which is preferably formed of angle irons with the horizontal sides facing upward, one of these sides forming the reduced 30 portion at 160, while the riser 162 is secured to the opposite side. When a step strikes the curve to the descending incline, the front wheels dip down while the rear wheels remain up, thereby tilting the step so that its 35 riser edge may go in under the front nosing of the next succeeding step.

In Figs. 20 and 21, I have shown the preferred form of the step and bracket construction. In this construction each wheel- 40 base is pinned to the axle and each bracket is provided with a pair of lateral wings 163 having outwardly extending flanges 164 which rest respectively upon the front arm of the wheel-base and a rear projection 165 45 thereof, the parts being secured by bolts 166 or other suitable means. The brackets are more or less rectangular in shape, and their upper portions are provided with exterior and interior bosses 26^a and 26^b, respectively, 50 bolted or otherwise attached to the tread or framework of the steps at each side of the axle, and at their inner ends they are provided with stirrups or collars 167, fitting on the axle 25 adjacent the hubs 33 of the 55 rack-links 30, the collars 167 being preferably formed with the small bearing lugs 168 which fit snugly against the aforesaid hubs 33, thus preventing any possible movement of the step transversely to the links, 60 and securing the alinement of the ends of the steps. By this construction I obtain a step structure of truss formation, in which the upper chord consists of the step-frame and the lower chord consists of the axle, the

chords being joined together at intermediate 65 points by the brackets. It is obvious that the construction by which the step-frame and wheel-base are connected together at the ends and at the additional points of connection between the ends provides a truss 70 formation, the intermediate connections being in the nature of ties or struts according to the character of the strains to which they are subjected and which they resist. This provides a very strong and rigid structure. 75 Each step unit consists of the step proper, the wheel-base and the step-frame, all connected in unitary form.

In Fig. 18 I show the balustrade provided with a lower member or curtain 169 which 80 is immediately adjacent to and passed by the ends of the steps, the curtain extending down to a point somewhat below the lower edge of the riser of the steps and secured to brackets 170 permitting its ready adjustment to compensate for warping. The wheels 23 and 24 are outside (away from the center of the machine) of the curtain which is placed to provide the minimum clearance with the ends of the steps, the wheels 24 90 traveling in the spaces back of the curtain.

By reference to Fig. 2 it will be seen that as the steps leave the horizontal run at or near the upper end-carriage they travel upon an upward curve and then there is a tangential run introduced joining the curve which leads to the descending incline, so that the curved path connecting the inclined and horizontal runs is really a compound of two curves with a straight or tangential run between them at which point the drive engages the descending line. By providing this curve rising above the horizontal the rear of each step is raised slightly above its succeeding step so that they may come into overlapping 100 position, and by providing the intermediate straight or tangential run I maintain the pitch line of the links uniform with reference to that of the drive wheel, as it is obvious that if one end of a link were entering 105 the curved path certain of its teeth at the other end would not correctly engage the sprocket. In practice I prefer to make this tangential run about two link lengths.

The plate girders 36 are provided with a 115 transverse diaphragm 171 located between the carrying and return runs or between the upper and lower series of steps, and which not only provides a diaphragm between the girders but forms a protector for the lower 120 run by reason of affording lodgment for the material of the upper run in case of accident.

While I have shown the various features of my invention as applied to stairways especially adapted for carrying passengers, it 125 will be understood that some features thereof might be applied to other kinds of power transmitting and conveying apparatus, and

that I do not desire to be limited to their employment in the particular kind of conveying apparatus shown and described.

While I have shown the various features 5 of my invention as embodied in the forms which I at present consider best adapted for carrying out their purpose, it will be understood that they are capable of modifications, and that I do not desire to be limited in the 10 interpretation of the following claims by the language thereof, but only as may be necessitated by the prior art.

What I claim as new and desire to secure by Letters Patent of the United States is:—

15 1. In a device of the class described, the combination with the series of connected steps, of inclined and horizontal ways in which said steps travel, and a driving mechanism intermediate the ends thereof near 20 the top of the incline and in continuous engagement with the step-connections of both the ascending and descending parts of said series.

25 2. In a device of the class described, the combination with a series of steps, of inclined and horizontal ways in which said steps travel, of a sprocket chain connecting said steps, and a sprocket wheel interposed between the ascending and descending series 30 of said steps intermediate the ends thereof near the top of the incline and constantly meshing with said chain on both sides.

35 3. In a device of the class described, the combination with a series of steps, and inclined and horizontal ways in which said steps travel, of a sprocket chain connecting said steps, a sprocket wheel interposed between the ascending and descending series 40 of said steps intermediate the ends thereof near the top of the incline in continuous mesh with said chain on both sides thereof, and means for applying power to said sprocket wheel to drive the steps.

45 4. In a device of the class described, the combination with a series of connected steps, of ways in which said steps travel, said ways including two landing portions at different levels and upper and lower inclined portions connecting the same, and driving mechanism for said steps located in the inclined portion adjacent to upper landing and having continuous engagement with the step-connections of both portions.

55 5. In a device of the class described, a series of connected steps, ways in which said steps travel in ascending and descending upper and lower runs, and a driving mechanism at the top of the incline intermediate the ends of the runs and engaging 60 the step-connections of both runs.

6. In a device of the class described, a series of connected steps, ways providing upper and lower inclined runs and horizontal landing portions, and a drive at the

top of the incline engaging the step-connections on both runs.

7. In a device of the class described, a series of connected steps, ways providing upper and lower inclined runs and horizontal landing portions, and a drive at the top 70 of the incline engaging the step connections on both runs, the ways being continuous at the end.

8. In a device of the class described, a series of connected steps, ways providing 75 upper and lower inclined runs and horizontal landing portions and a drive at the top of the incline engaging the step connections on both runs, the ways being continuous and of varying length at the end.

80 9. In a device of the class described, the combination with a series of steps, of ways in which said steps travel, said ways including two landing portions at different levels and an inclined portion connecting the same, a chain connecting said steps, and driving mechanism for said chain located in the inclined portion adjacent to the upper landing.

10. In a device of the class described, the combination with a series of steps, and ways in which said steps travel, said ways including two landing portions at different levels and an inclined portion connecting the same, of a sprocket chain connecting said steps, 95 and a sprocket wheel interposed between the ascending and descending series of said steps and located in the inclined portion adjacent to the upper landing and meshing with both the ascending and descending portions of said chain.

105 11. In a device of the class described, the combination with a series of steps connected by a driving chain, of ways in which said steps travel, said ways including landing portions at different levels and an inclined portion connecting the same, driving mechanism for said chain located in the inclined portion adjacent to the upper landing to reduce the weight on the chain at the angle.

110 12. In a device of the class described, a conveyer having ascending and descending runs of connected sections, a drive near the top of the incline engaging on both runs the connections of the sections of the conveyer, 115 and means for relieving the drive of part of the weight of the conveyer on the incline.

13. In a device of the class described, a conveyer having ascending and descending inclined runs of connected sections, a drive 120 engaging both runs of the conveyer, and an idler engaging both runs of the conveyer on the incline and on which the weight thereof down the incline hangs.

125 14. In a device of the class described, a conveyer having ascending and descending inclined runs of connected sections, a drive engaging both runs of the conveyer at or

near the top of the incline, and an idler engaging both runs upon the incline.

15. In a device of the class described, upper and lower inclined ways, a moving stairway traveling on the ways and consisting of link-connected steps, a driving sprocket engaging the links on both runs at an incline, and an idler sprocket also engaging the links of both runs on the incline, where 5 by one of such sprockets carries the load of the steps between such sprocket and the other sprocket, and such other sprocket carries the load between itself and the bottom of the incline.
15. 16. In a device of the class described, a traveling stairway providing upper and lower inclined runs, and a drive sprocket and an idler sprocket engaging both runs at different points on the incline to divide up 10 the load of the steps.

17. In a device of the class described, a conveyer having ascending and descending runs, a drive engaging both runs of the conveyer at the incline, and an idler interposed 20 between the drive and the bottom of the incline and engaging both runs.

18. In a device of the class described, a conveyer having ascending and descending inclined runs, a drive coöperating with both runs at or near the top of the incline, and an idler interposed between the drive and the bottom of the incline and engaging both runs.

19. In a device of the class described, a conveyer having ascending and descending inclined runs, a driving sprocket engaging both runs at or near the top of the incline, and an idler sprocket also engaging both runs at a point between the ends of the incline, one of such sprockets carrying the load between such sprocket and the other, and the other sprocket carrying the load between itself and the bottom of the incline.

20. In a device of the class described, a moving stairway having ascending and descending runs and consisting of an endless series of steps, ways on which the steps travel, rack links connecting the steps, a drive-shaft located near the upper end of the incline and having a sprocket engaging the links of both runs, and a cross shaft located between the drive shaft and the bottom of the incline and having an idler engaging the links of both runs.

21. In a device of the class described, a conveyer having inclined runs of connected sections, a drive for the conveyer engaging near the top of the incline both runs to support the weight thereof down the incline.

22. In a device of the class described, the combination with the moving series of connected sections, of guides for said sections stationary relative to the movement thereof supporting said sections at both ends 60 throughout their entire course, and driving

mechanism continuously engaging the sections on both runs between the two ends of the course and at a point where they change direction of movement.

23. In a device of the class described, the combination with a series of steps, of ways in which said steps travel, driving mechanism engaging with said steps, and brake mechanism to prevent the backward movement of said steps consisting of a recessed 75 collar surrounding the driving shaft and the rollers interposed between said collar and shaft in the recesses; all constructed and operating substantially as described.

24. In a device of the class described, the combination with the series of connected sections moving throughout their course in a single vertical plane, of guides for said sections stationary relative to the movement thereof and supporting them at both ends 85 throughout their entire course, and driving mechanism in continuously driving engagement with the sections between the two ends of the course and at a point where they change direction of movement, said driving mechanism also engaging the sections 90 on the return run.

25. In a device of the class described, the combination with a series of connected steps, of ways in which said steps travel, said ways 95 including a horizontal landing portion and an inclined portion leading thereto, and driving mechanism for said steps located in the inclined portion adjacent to the landing and engaging the step-connections.

26. In a device of the class described, the combination with the series of steps, of ways in which said steps travel, said ways including a horizontal landing portion to which an inclined portion leads, and driving mechanism for said steps located in the inclined portion adjacent to the landing and 105 engaging with both the ascending and descending parts of said series.

27. In a device of the class described, the combination with a series of steps, of ways in which said steps travel, said ways including a horizontal landing portion to which the inclined portion leads, of a 110 sprocket chain connecting said steps, and a sprocket wheel interposed between the ascending and descending series of said steps and located in the inclined portion adjacent to the landing and meshing with both the ascending and descending portions of said chain.

28. In a device of the class described, the combination with a series of connected steps, inclined and horizontal ways in which said steps travel, and a single rotary member 115 intermediate the ends thereof near the top of the incline continuously engaging the step-connections of both the ascending and descending portions of said series.

29. In a device of the class described, the 120

- combination with an endless carrier composed of a series of connected sections, of inclined and horizontal runs for said carrier, and a drive intermediate the ends thereof in continuous engagement with both the ascending and the descending portion of said carrier and engaging the latter portion in a tangential run intermediate the inclined and horizontal runs.
30. In a device of the class described, the combination with an endless carrier composed of a series of connected sections, of inclined and horizontal runs for said carrier, and driving mechanism intermediate the ends thereof in continuous engagement with both the ascending and descending portions of said carrier and engaging the latter in a tangential run located in the curve between the inclined and horizontal runs.
31. In a device of the class described, the combination with an endless carrier composed of a series of connected sections, of guiding and supporting mechanism for said carrier, said mechanism including a landing portion and an inclined portion leading thereto and driving mechanism for said carrier located in the inclined portion adjacent to the landing and engaging the ascending and descending portions of the carrier in straight runs.
32. In a device of the class described, the combination with an endless carrier composed of a series of connected sections, of guiding and supporting mechanism for said carrier, said mechanism including a horizontal landing portion to which an inclined portion leads, and driving mechanism for said carrier located in the inclined portion adjacent to the landing and engaging with both the ascending and descending parts of said carrier in straight but non-parallel lines.
33. In a device of the class described, the combination with a series of connected sections moving throughout their course in a single vertical plane, of guides for said sections stationary relative to the movement thereof and supporting them at both ends throughout their entire course, and driving mechanism engaging the sections between the two ends of the course and at a point where they change direction of movement, said driving mechanism consisting of a sprocket wheel in continuous engagement with said steps on both the forward run and return run.
34. The combination in a moving platform or stairway, of the moving connected steps, tracks therefor, and a driving mechanism in continuous engagement with the connections of said steps between the two ends of the platform or stairway and at a point where they change direction of movement, said driving device also engaging the step connections on the return run, substantially as described.
35. The combination in a moving platform or stairway of moving sections, guides therefor, and a constantly acting driving device engaging the sections between the two ends of the platform or stairway and at a point where they change direction of movement, said driving device also engaging the sections on the return run, substantially as described.
36. In a device of the class described, the combination with a series of steps connected by a central driving chain, of ways on which said steps travel, said ways including landing portions at different levels and an inclined portion connecting the same, and a driving wheel for said chain located in the inclined portion adjacent to the upper landing to reduce the tension of the chain at the angle.
37. In a conveying apparatus, the combination with the ways extending to different levels, of a series of connected steps coöperating with said ways, and a drive wheel for said steps coöperating therewith to remove the tension thereon while passing portions of the ways.
38. In a conveying apparatus, the combination with the ways extending to different levels, of a series of connected steps coöperating with said ways, and a driving wheel coöperating therewith to establish tension in a portion thereof and remove it on another portion.
39. In a conveying apparatus, the combination with the ways extending to different levels, of a series of connected steps coöperating with said ways, and a driving wheel coöperating with said steps to establish tension therein as they pass between predetermined points on said ways, and remove it between other points.
40. In a device of the class described, an inclined way, a conveyer composed of bearing sections, links connecting the sections, a drive located near the top of the incline and continuously engaging the links of the ascending and descending runs.
41. In a device of the class described, an inclined way, a conveyer composed of bearing sections, links connecting the sections, a drive located near the top of the incline and engaging the links of the ascending and descending runs to drive and suspend the same.
42. In a device of the class described, a conveyer consisting of a series of connected steps moving in a continuous path, and driving mechanism therefor contained within the body of the machine.
43. In a device of the class described, a conveyer consisting of a series of connected steps, a way providing an upper carrying and a lower return run, and driving mechanism located between the runs.
44. In a traveling stairway having a

framework, and an endless flight of steps mounted therein, the steps being journaled to an endless chain, the journals of which travel in the double camway, said camway 5 being located outside of the vertical plane of the moving flight of steps, substantially as and for the purpose described.

45. In a traveling conveyer, the combination of a chain composed of a series of connected links, and a series of steps each pivoted midway between its front and rear sides to one of said links.

46. In a traveling conveyer, the combination of a series of steps having downwardly 15 extending end portions provided with bearings on their outer faces, and an endless belt located between said end portions and pivotally secured thereto.

47. In a device of the class described, the combination with the ways, of the trucks 20 having axles, the chain links connecting said axles and consisting of the male links having the sleeves formed on their ends fitting over the axles and into the larger sleeves at 25 the ends of the female links.

48. In a device of the class described, the combination with the ways, of the trucks, a bolster rod on each truck, and chain links connecting said bolster rods and consisting 30 of the male and female links, the male links having the sleeves formed on their ends surrounding the bolster rods, said sleeves fitting in the larger sleeves at the ends of the female links.

49. In a device of the class described, the combination with the ways, of the trucks, and chain links connecting said trucks and consisting of the side bars having their sleeves formed on their ends and connected 40 by the rods, the sleeves on the alternate links being similar and fitting into the sleeves of the adjacent links; substantially as described.

50. In a device of the class described, the combination with the ways, of the trucks, a bolster rod on each truck, and chain links connecting said trucks and consisting of the male and female links, made up of side bars connected by rods, the male links provided 50 with the sleeves at the ends of the side bars through which the bolster rods pass and which pass into the sleeves at the ends of the female links.

51. In a device of the class described, the combination with trucks having bolster rods, of links connecting said bolster rods to form said trucks into an endless series, step supporting brackets on each bolster rod on either side of said links and having a collar 60 engaging the links, and a step rigidly secured on said brackets.

52. In a device of the class described, a wheel-supported step having the wheel associated with the riser extending beyond the same.

53. In a device of the class described, a step having front and rear supporting-wheels, the wheel associated with the riser being located beyond the riser.

54. In a device of the class described, a series of connected steps each of which is provided with front and rear supporting wheels, the rear wheels being located beyond the step riser.

55. In a device of the class described, a step the wheel-base of which is wider than the step.

56. In a device of the class described, a step having its wheel-base wider than the tread thereof.

57. A step for an elevator having a wheel-base broader than the tread.

58. In a device of the class described, a step provided with wheel-carrying arms of equal length and extending beyond the tread.

59. In a device of the class described, a step provided with wheel-carrying arms of equal length and extending beyond the opposite sides of the step tread, the center line through the arms being parallel with the tread.

60. In a device of the class described, a way, a series of steps provided with axles, oppositely extending wheel-carrying arms of equal length on the axles, the center line 95 through the arms of each step being parallel with the tread.

61. In a device of the class described, a way consisting of upper and lower inclined tracks having end portions in the same horizontal plane, a series of connected steps provided with axles, oppositely extending wheel-carrying arms of equal length, the wheels thereof engaging the tracks to maintain the steps with their treads horizontal throughout the transporting run, and driving means 105 engaging the step-connections.

62. In a device of the class described, a step-frame having bosses, and a tread bolted to the bosses.

63. In a device of the class described, a step-frame having inner and outer bosses, and a tread bolted to the bosses.

64. In a device of the class described, a step and wheel-carrying arms connected together to form a unitary structure.

65. In a device of the class described, a step, and a wheel-carrying arm united to the step-frame.

66. In a device of the class described, a series of steps, and wheel-carrying arms, such steps and arms being fixed together to provide units, and links pivotally connecting such units whereby the latter are free to turn independently of the links.

67. In a device of the class described, the combination with tracks forming a way, wheel-carrying arms rigid with the steps, and links pivotally connecting the steps.

68. In the device of the class described,

- the combination with tracks forming a way, of a series of steps having arms provided with carrying-wheels adapted to the tracks, and links connecting the steps inside the 5 arms. 70
69. In a device of the class described, the combination with tracks forming a way, of steps having axle-bars, links connecting the axle-bars, and wheel-carrying arms on the 10 axle-bars outside the links. 75
70. In a device of the class described, the combination with tracks forming a way, of a series of steps having arms provided with carrying-wheels adapted to the tracks, and 15 pin links of constant length connecting the steps. 80
71. In a device of the class described, the combination with tracks forming a way, of a series of steps having arms provided with 20 carrying-wheels adapted to the tracks, and links of constant length connecting the steps, and drive mechanism engaging the links. 85
72. In a device of the class described, a series of steps, and a chain having interconnected sections connecting the steps intermediate the ends thereof. 90
73. In a device of the class described, the combination with tracks forming a way, of steps having axle-bars, yokes mounted on 30 the axle-bars and provided with wheels adapted to the tracks, male links connecting alternate pairs of steps, and female links alternating with the male links and pivoted on the latter. 95
74. In a device of the class described, a series of steps, and a chain having rigid links connecting the steps. 100
75. In a device of the class described, a way, steps traveling thereon, a chain having 40 links of fixed length connecting the steps under the treads thereof, and means engaging the chain to drive the steps. 105
76. In a device of the class described, a way, wheeled steps traveling on the way 45 and each provided with an axle, links of constant length intermediate the ends of the steps and connecting the axles, and a driving device engaging the links. 110
77. In a device of the class described, a way consisting of tracks having inclined 50 and horizontal portions, axles on the steps, oppositely extending arms fixed to the axles and having wheels traveling on the tracks, links connecting the axles intermediate the 55 ends thereof, and a driving wheel engaging the links. 115
78. In a device of the class described, a way having inclined and horizontal runs, a series of steps having curved risers each of 60 which is in contact with the adjacent step throughout the transporting run, links of constant length connecting the steps, and means to move the steps. 120
79. In a device of the class described, a way having inclined and horizontal runs, 65 125
- a series of connected steps providing a stair formation on the incline and horizontal end landings, each step being provided with a convex riser which is in contact with the adjacent step both on the incline and landings, links of constant length connecting the steps, and means to drive the steps. 70
80. In a device of the class described, a way, a series of steps having overlapping wheel-carrying arms and convex risers which contact with the treads of adjacent steps. 75
81. In a device of the class described, a way consisting of inclined tracks having horizontal end portions, a series of connected steps having overlapping wheel-carrying arms and breaking into step-like formation on the incline and forming landings on the horizontal portions, each step having a convex riser which engages the adjacent 85 step on the incline as well as at the landings. 85
82. In a device of the class described, a step having wheel-carrying arms, one of which diverges from the vertical plane of the other. 90
83. In a device of the class described, a step, and oppositely extending wheel-carrying arms, one of which diverges from the vertical plane of the other arm to a different vertical plane. 95
84. In a device of the class described, a step, a wheel-base comprising forwardly and rearwardly extending arms arranged in different vertical planes. 100
85. In a device of the class described, a step frame having a wheel-base, a stirrup depending from and rigid with the step-frame, and an axle secured to the wheel-base and stirrup, providing a truss construction in which the axle is the lower cord and the 105 step-frame the upper cord. 105
86. In a device of the class described, a step-frame and wheel-base, an axle connected at its ends to the wheel-base and at intermediate points to the step-frame. 110
87. In a device of the class described, a step-frame, a wheel-base secured thereto, an axle-bar secured thereto at its ends and intermediate connections between the axle to the step-frame. 115
88. In a device of the class described, a step-frame, a wheel-base secured thereto, an axle-bar passing through and pinned at its ends to the base, and connections securing the axle to the step-frame intermediate the 120 ends of the axle. 120
89. In a device of the class described, a way having an end-carriage having tracks to reverse the steps at the upper landing, and a step no portion of which rises above 125 the landing in passing through the carriage. 125
90. In a device of the class described, a way consisting of an incline and a horizontal landing portion, an end-carriage having tracks to reverse the steps, and a series of 130

steps traveling on the way and entering the carriage without rising above the landing.

91. In a device of the class described, a continuous way comprising inclined, horizontal, and curved end tracks, a series of connected steps moving on the way, and wheel-carrying arms rigid with the steps.

92. In a device of the class described, a continuous way comprising inclined, horizontal, and curved end tracks, a series of steps moving on the way, links pivotally connecting the steps, and wheel-carrying arms rigid with the steps.

93. In a device of the class described, a continuous way comprising inclined, horizontal, and curved end tracks, a series of steps moving on the way, links pivotally connecting the steps, and arms rigid with the steps and each having two wheels adapted to continuously support the step on the carrying run.

94. In a device of the class described, a step having a wheel-base wider than the step, and tracks in different vertical planes coöoperating with each end of the wheel-base.

95. In a conveyer, a step and wheel-carrying arms connected together to form a unitary structure, the front and rear portions of the arms being in different vertical planes.

96. In a device of the class described, a conveyer consisting of a series of steps each having an axle and each comprising brackets and a wheel base pinned to an axle, and a drive chain connecting the axles.

97. The combination in a moving stairway, of two curved guides connected together at top and bottom by inclined ways, step sections each having a curved riser, the curves of the risers being such that the step sections will be close together while their relative positions are changing, and means for driving said step sections.

98. In a device of the class described, a way, and a vertically adjustable end carriage provided with tracks.

99. In a device of the class described, a way, and a vertically and longitudinally adjustable end carriage provided with tracks.

100. In a device of the class described, a series of wheeled steps, upper and lower trackways, and a vertically and longitudinally adjustable end-carriage having tracks connecting the trackways.

101. In a device of the class described, upper and lower trackways, and an automatically adjustable end-carriage connecting the trackways.

102. In conveying apparatus, a series of connected steps, upper and lower runs upon which the steps move, an adjustable end-carriage between the runs and having a continuous guide to coöperate with the steps while passing from one run to the other.

103. In a device of the class described, upper and lower trackways, and an auto-

matically adjustable end-carriage provided with tracks connecting the trackways.

104. In a device of the class described, upper and lower trackways, and an automatically adjustable carriage connecting the trackways at each end.

105. In a device of the class described, a moving footway, tracks therefor, and an end-carriage for reversing the direction of movement of the footway, and means for automatically moving the carriage in the direction of movement of the footway.

106. In a device of the class described, upper and lower trackways connecting the different levels, steps adapted to the trackways, and a carriage connecting the trackways at the lower level, and means normally moving the carriage in the direction of movement of the footway to produce slack therein.

107. In a device of the class described, upper and lower trackways, the former consisting of horizontal end portions and an inclined portion connecting the same, a carriage connecting the trackways at each end, and means associated with each carriage for automatically moving the same in the direction of movement of the footway.

108. In a device of the class described, upper and lower trackways, the former consisting of horizontal end portions and an inclined portion connecting the same, an end carriage connecting the trackways at each end, means to automatically move the upper carriage to take up slack in the footway, and means for moving the lower carriage to produce slack in the footway as the latter passes from the lower horizontal portion to the incline.

109. In a device of the class described, upper and lower trackways, upper and lower carriages connecting the trackways at each end, and means associated with each carriage to normally move the same in the same direction.

110. In a device of the class described, the combination with a series of connected steps, of ways for said steps consisting of the stationary center portion and an end portion automatically movable to and from said stationary portion; substantially as described.

111. In a device of the class described, the combination with the endless carrier, of guiding and supporting mechanism for said carrier consisting of the stationary center portion and the end portion automatically movable to and from said stationary portion.

112. In a device of the class described, the combination with a series of steps, of links connecting the same, and tracks for said steps consisting of the stationary center portion and the end portion automatically movable to and from said stationary portion.

113. In a device of the class described, the

combination with a series of connected steps, of ways for said steps consisting of the stationary center portion and the movable end portions, and means for moving said end portions automatically to and from said stationary portion to keep the chain of steps in proper adjustment.

114. In a device of the class described, the combination with a series of connected steps, of ways for said steps consisting of the stationary center portion and the movable end portions, and means for moving said end portions automatically to keep the chain of steps taut consisting of weights suspended so as to move said end portions away from the stationary portion.

115. In a device of the class described, the combination with a series of steps, of ways for said steps consisting of the inclined stationary portion and the horizontal movable end portion, and means for moving the end portion automatically toward the inclined portion for the purpose described.

116. In a device of the class described, the combination with a series of connected steps, of ways for said steps consisting of the stationary central portion and a movable end portion, and means for raising or lowering said end portion for the purposes described.

117. In a device of the class described, the combination with a series of connected steps, of ways for said steps made up of tracks and consisting of the stationary center portion and the movable end portion, and means for moving said end portion automatically to keep the chain of steps in proper adjustment.

118. In a device of the class described, the combination with a series of steps, links connecting the same, with tracks for said steps consisting of the stationary center portion and the movable end portion, and means for raising and lowering said end portion to keep the tracks in alignment.

119. In a device of the class described, the combination with an endless series of connected steps, of supporting and guiding means for said steps throughout their circuit, one of the ends of said circuit being automatically movable to and from the central portion for the purpose described.

120. In a device of the class described, upper and lower horizontal tracks, inclined tracks, step sections arranged to travel on said tracks, a drive chain for driving said step sections, guides at each end of the stairway for the step sections, the guides at the lower end of the stairway being adjustable.

121. In a device of the class described, the combination with a series of connected steps provided with rollers, links connecting said steps, with tracks for said steps consisting of the stationary central portion and the movable end portion, the tracks of said stationary and movable portions being pro-

vided with reduced ends so that the two sets of tracks can be telescoped upon each other, said telescoped portions being arranged so that the wheels will ride on both the stationary and movable sections of the tracks where they overlap.

122. In a device of the class described, the combination with a series of connected steps, of ways for said steps consisting of the stationary center portion and the movable end portion, said movable end portion consisting of the plates supporting the tracks connected by the sleeve; substantially as described.

123. In a device of the class described, the combination with a series of connected steps, of ways for said steps consisting of the stationary central portion and the movable end portion, a support for said end portion, and anti-friction rollers interposed between the support and end portion.

124. In a device of the class described, the combination with a series of connected steps, of ways for said steps consisting of the stationary central portion and the movable end portion, a movable support for said end portion, and anti-friction rollers interposed between said movable support and main frame.

125. In a device of the class described, the combination with an endless series of connected steps, of ways for said steps consisting of the stationary central portion and the movable end portion, a support for said end portion provided with a flange, a stationary flange beneath the flange on the support, and anti-friction rollers interposed between said flanges.

126. In a device of the class described, the combination with a series of connected steps, of ways for said steps consisting of the stationary central portion and the movable end portion, anti-friction rollers for supporting said end portion, and means for raising and lowering the supports for said anti-friction rollers; substantially as described.

127. In a device of the class described, the combination with a series of connected steps, of ways for said steps consisting of the stationary central portion and the movable end portion, anti-friction rollers for supporting said end portion, and means for raising and lowering the supports for said anti-friction rollers consisting of the stationary support having the inclined upper surface and the anti-friction roller support having the inclined under surface, and means for moving the anti-friction roller support longitudinally of the stationary support.

128. In a device of the class described, a way consisting of upper and lower tracks, and an end carriage for reversing the direction of movement of the steps between the tracks and having the curves thereof compounded for constant speed.

129. In a device of the class described, a series of connected steps, tracks in which

said steps travel and including end portions at different levels and an inclined portion connected to the same by curves compounded for constant speed.

5 130. In a device of the class described, a series of connected steps, tracks in which said steps travel and including upper and lower inclined portions and end portions and end-carriages, forming a continuous circuit and having its curves compounded for constant speed.

131. In a conveyer, the combination of a bearing surface, with supports consisting of tracks of varying length and unbroken continuity.

132. In a conveyer the combination of a bearing surface with supports consisting of tracks of automatically varying length and unbroken continuity.

20 133. In a device of the class described, the combination with ways having inclined and horizontal portions of varying length, of a series of steps moving on the ways, and an endless drive chain to which the steps are pivotally attached.

134. The combination in a moving stairway, of two adjustable end-carriages each having curved guides connected at top and bottom by inclined ways, step sections 30 adapted to travel in an endless path up one incline and through an end-carriage, and down the other incline and through the other end-carriage, and means for driving said sections.

35 135. In a device of the class described, the combination with a way, of an end-carriage at the terminal of the way and provided with bearing portions at different levels, stationary tracks associated with the said bearing 40 portions, and an anti-friction roller interposed between each bearing portion and its associated track.

136. In a device of the class described, the combination with the carrier and means for 45 driving it, of double shunt belts at the landing, and means for moving said belts in opposite directions.

137. In a device of the class described, the combination with the carrier and means for 50 driving it, of double shunt belts at the landing, and means for moving said belts in opposite direction and synchronously with the carrier by means of a single driving belt or rope.

55 138. In a device of the class described, the combination with the carrier, of belt rollers at the edges thereof, coöperating belt rollers at the center thereof and in advance of the first rollers, shunt belts respectively connecting said edge and center rollers in pairs, and means for driving said edge rollers in opposite directions.

139. In a device of the class described, the combination with the carrier, of belt rollers 60 at the edge thereof, coöperating belt rollers

at the center thereof and in advance of the first rollers, one center belt roller being slightly in advance of the other, belts respectively connecting said edge and center rollers in pairs, and means for driving said edge rollers in opposite directions.

140. In a device of the class described, the combination with the carrier, of the vertical shafts 141 and 143 at the edges thereof having the belt rollers 146 and 147 on their lower ends and the pulleys 142 and 144 on their upper ends, the coöperating belt rollers 150 and 151 at the center of said carrier in advance of the rollers 146 and 147, the belts 152 and 153 connecting said rollers 146 and 150, and 147 and 151 respectively, a crossed belt 145 coöperating with the pulleys 142 and 144, and means for rotating the shaft 141.

141. In a device of the class described, the combination with the carrier, and means for driving it including the shaft 101, of the shunt mechanism consisting of a pair of vertical belt rollers arranged above the carrier, a belt connecting said rollers, a shaft 90 upon which one of said rollers is secured, a pulley upon said shaft, a belt connecting said two pulleys, and guide pulleys for said belt.

142. In a device of the class described, the combination of the carrier, and means for driving it including the shaft 101, of the double shunt mechanism consisting of the vertical shafts 141 and 143 at the edges of the carrier having the belt rollers 146 and 147 respectively secured at the lower portions thereof and the pulleys 142 and 144 secured at the upper end thereof, the coöperating belt rollers 150 and 151 in the center thereof in advance of the rollers 146 and 147, the belts 152 and 153 connecting said rollers 146 and 150, and 147 and 151, respectively, the crossed belt 145 coöperating with the pulleys 142 and 144, a pulley 140 on the lower end of the shaft 101, belts connecting the pulleys 131 and 140, and guide pulleys for one of said belts including the pulleys 138 and 139.

143. In a device of the class described, the combination with the carrier, and means for driving it, of a shunt belt running diagonally across said carrier, and means for driving said shunt belt so that the ratio of the lineal speed of the carrier to that of the shunt belt is not greater than that of the cosine of the angle between them is to 1.

144. In a device of the class described, the combination with the carrier, and means for driving it, of a shunt belt running diagonally across the carrier and driven by the same means, and connections between said carrier and shunt belt so that the ratio of the lineal speed of the carrier to that of the shunt belt is not greater than that of the cosine of the angle between them is to 1.

145. In a device of the class described, a conveyer, and a shunt consisting of a belt driven at such speed that the resultant speeds of the conveyer and shunt produce motion laterally to the direction of travel of the conveyer. 65
146. In a device of the class described, a conveyer, and a shunt traveling at such greater speed than the conveyer that the resultant motion is at a right angle to the direction of movement of the conveyer. 10
147. In a device of the class described, a moving stairway and a belt crossing the landing portion of the stairway at an angle 15 and at such speed that its forward component of movement is at least equal to the rate of movement of the steps.
148. In a device of the class described, a moving conveyer consisting of a series of connected steps, a way upon which the steps run, a hand rail, a shunt, and connections to drive the shunt and hand rail from the conveyer. 20
149. An endless hand-rail of substantially inverted U-shape and having a continuous hand-grasp surface both cross-sectionally and lengthwise of the same. 25
150. In a device of the class described, a guide, and an endless hand-rail having inverted edges engaging the guide. 30
151. In a device of the class described, a stationary guide, and a continuous hand-rail of substantially inverted U-shape in cross-section. 35
152. A jointless hand-rail of substantially inverted U shape in cross-section. 40
153. A hand-rail consisting of a plurality of strips and a coating of rubber or the like connecting the strips. 45
154. A hand-rail consisting of rubber coated strips. 50
155. In a device of the class described, the combination with the carrier and means for driving it, of a stationary undercut guide substantially parallel to the working surface of said carrier, a continuous flexible hand rail having an inner cross-section adapted to embrace the stationary hand rail, and means for driving said hand rail in synchronism with the carrier. 55
156. In a device of the class described, the combination with the carrier and means for driving it, of a stationary hand rail substantially parallel to the working surface of said carrier, a continuous jointless flexible hand rail adapted to embrace said stationary hand rail, and means for driving said flexible hand rail in synchronism with the carrier. 60
157. In a device of the class described, the combination with the carrier and means for driving it, of a stationary hand rail substantially parallel to the working surface of said carrier, a continuous flexible hand rail made of rubber adapted to embrace the stationary 65
- hand rail, and means for driving said hand rail in synchronism with the carrier. 70
158. In a device of the class described, the combination with the carrier and means for driving it, of a stationary undercut hand rail substantially parallel to the working surface of said carrier, a continuous flexible hand rail made of rubber and having an inner cross-section adapted to embrace the stationary hand rail and having the correspondingly shaped metallic strips embedded therein transversely for the purpose described, and means for driving said hand rail in synchronism with the carrier. 75
159. In a device of the class described, a moving hand-rail for a conveyer, a drive for the hand-rail at each end of the conveyer, and means to transmit motion from the conveyer to the hand-rail drives. 80
160. An inclined conveyer, a hand-rail therefor driven at the top and bottom terminals, and means to transmit motion from the conveyer to the hand-rail drives. 85
161. In a device of the class described, a moving hand-rail, a guide therefor having a lower horizontal run and an inclined run, and a drive for the rail at each end. 90
162. In a device of the class described, a moving hand-rail, a guide therefor having a lower horizontal run and an inclined run, and drive mechanism for said rail adapted to produce slack in the rail where it changes its direction of movement. 95
163. In a device of the class described, a conveyer, and a hand-rail therefor driven therefrom. 100
164. In a device of the class described, a moving footway, and a traveling hand-rail therefor driven by a connection from the footway. 105
165. In a device of the class described, a moving footway consisting of an endless series of steps, links connecting the steps, and means engaging the links to move the steps, a traveling hand-rail, and a connection driven by the links to drive the hand-rail. 110
166. In a device of the class described, the combination with the carrier and means for driving it, of a flexible unitary hand-rail, guide pulleys upon which it is mounted at the ends thereof, and driving mechanism for one of said pulleys. 115
167. In a device of the class described, the combination with the carrier and means for driving it, of a flexible hand rail, guide pulleys upon which it is mounted at the ends thereof, a shaft driven by the carrier and having a pulley wheel thereon, a second pulley wheel connected to said guide pulley, and a belt connecting said pulley wheels. 120
168. In a device of the class described, the combination with the carrier and means for driving it, of a flexible hand rail, guide pulleys upon which it is mounted at the ends 125

thereof, and driving mechanism for one of said pulleys including a shaft driven by the carrier having a pulley wheel thereon, a second pulley wheel connected to said guide 5 pulley, a belt connecting said pulley wheels, and the guide pulleys 93 and 94 for said belt so located as to hold the belt upon said second guide pulley.

169. In a device of the class described, the 10 combination with the carrier and means for driving it, of a flexible hand rail, a guide pulley at one end thereof over which the rail runs, an endless belt so located as to press the hand-rail upon the guide pulley, and means for driving said belt and thereby the hand rail.

170. In a device of the class described, the 15 combination with the carrier and means for driving it, of a flexible hand rail, a guide pulley at one end thereof over which the rail runs, a pair of belt wheels located adjacent to said guide pulley, an endless belt upon said belt wheels serving to press the hand rail upon the guide pulley, and means for 20 driving said belt wheels.

171. In a device of the class described, the 25 combination with the carrier and means for driving it, of a flexible hand rail, a guide pulley at one end thereof over which the rail runs, a pair of belt wheels located adjacent to said guide pulley, an endless belt upon said belt wheels serving to press the hand rail upon the guide pulley, and means for 30 driving said belt wheels consisting of the pulley wheels 94 and 93 upon the same shafts as the belt wheels and a driving rope co-operating with said pulley wheels.

172. In a device of the class described, the 35 combination with the carrier and means for driving it, of a flexible hand rail, a guide pulley at one end thereof over which the rail runs, a guide pulley connected to said pulley, a pair of belt wheels located in the same plane as the guide pulley and adjacent 40 thereto for the purpose described, an endless belt on said belt wheels serving to press the hand rail against the guide pulley, a pair of pulley wheels on the same shafts as the belt wheels, and a single driving rope 45 co-operating with all three of the pulley wheels; substantially as described.

173. In a device of the class described, the 50 combination with the carrier and means for driving it, of a flexible hand rail, a guide pulley at one end thereof over which the hand rail runs, belt wheels located adjacent to said guide pulley, means for adjusting the position of said belt wheels, an endless belt upon said belt wheels co-operating with 55 the hand rail and guide pulley for the purpose described.

174. In a device of the class described, the 60 combination with the carrier and means for driving it, of a flexible hand rail, a guide pulley at one end thereof over which the

hand rail runs, means for adjusting said guide pulley longitudinally of the belt, belt wheels adjacent to said guide pulley, means for adjusting said belt wheels to and from said guide pulley, and the belt upon said 70 belt wheels co-operating with the hand rail and the guide pulley for the purpose described.

175. In a device of the class described, a hand-rail, means to drive the rail, and 75 means to press the rail upon its driving means.

176. In a device of the class described, a hand-rail, means to drive the rail and an adjustable member contacting the rail at or 80 near the driving means without changing the normal direction of flexure thereof.

177. In a device of the class described, the combination with the series of steps, and means for driving the same, of ways for 85 said steps arranged so that the threads of said steps form a stairway on the incline and a horizontal surface on the landings, an endless hand rail having alternate portions thereof the length of the width of a tread 90 of different appearance, and means for driving said hand rail in synchronism with the movement of the steps.

178. In a device of the class described, the combination with the stationary under-cut 95 rail, of a continuous flexible hand-rail, having an interior cross-section adapted to embrace the hand-rail, and means for driving said flexible hand-rail.

179. In a device of the class described, the 100 combination with a stationary under-cut hand rail, of a continuous flexible hand-rail made of rubber and having an interior cross-section adapted to embrace the stationary hand-rail and having correspondingly shaped rigid strips embedded therein transversely for the purpose described, and means for driving said hand-rail.

180. In a device of the class described, the 105 combination with a flexible hand-rail, of a guide pulley at one end thereof over which the hand-rail runs, an endless belt so located as to press the hand-rail upon the guide pulley, and means for driving said belt and thereby the hand rail.

181. As a new and useful article of manufacture, a flexible hand-rail adapted to fit on a rigid under-cut rail, and having an interior cross-section adapted to embrace the rigid rail to prevent its being lifted therefrom.

182. As a new and useful article of manufacture, a flexible hand-rail adapted to fit on a rigid under-cut rail, and having an interior cross-section adapted to embrace the 125 rigid rail to prevent its being lifted therefrom and having correspondingly shaped strips embedded therein transversely to retain its shape.

183. A conveyer consisting of a series of 130

moving steps, and an entrance landing adapted to respond to the rhythmic movement of the steps.

184. A conveyer consisting of a series of 5 moving steps, and an entrance landing consisting of a flexible mat which responds to the movement of the steps as they travel into position to receive a passenger.

185. A conveyer consisting of a series of 10 moving steps, an entry landing therefor, and a flexible mat at the landing adapted to receive the impact of the steps as they pass to position at the landing.

186. In a device of the class described, the 15 combination with the series of steps, and means for driving the same, of ways for said steps arranged so that the treads of said steps form a stairway on the incline and a horizontal surface on the landing, and a 20 flexible cover for a portion of the landing, such as the mat 126.

187. In a device of the class described, a moving stairway, an entrance landing, and a signal which is automatically actuated as the 25 steps pass to the said landing.

188. In a device of the class described, the combination with the series of steps, and means for driving the same, of ways for said steps arranged so that the treads of said 30 steps form a stairway on the incline and a horizontal surface on the landings, and an alarm sounded each time the steps have advanced a distance equal to the width of one of the treads.

189. In a device of the class described, the combination with the series of steps and means for driving the same, of ways for said steps arranged so that the treads of said steps form a stairway on the incline and a 40 horizontal surface on the landings, a flexible covering for a portion of a landing such as the mat 126, and an alarm sounded each time the steps have advanced a distance equal to the width of one of the treads.

190. In a device of the class described, the combination with the series of steps and means for driving the same, of ways for said steps arranged so that the treads of said 50 steps form a stairway on the incline and a horizontal surface on the landings, a flexible covering for a portion of the landing, such as the mat 126, an endless hand rail having alternate portions thereof the length of the width of a tread of different appearance, and 55 means for driving said hand rail in synchronism with the steps.

191. In a device of the class described, the combination with the series of steps and means for driving the same, of ways for said 60 steps arranged so that the treads of said steps form a stairway on the incline and a horizontal surface on the landings, an alarm sounded each time the steps have advanced a distance equal to the width of one of the 65 treads, an endless hand rail having alternate

portions thereof the length of the width of a tread of different appearance, and means for driving said hand rail in synchronism with the movement of the steps.

192. In a device of the class described, 70 the combination with the series of steps and means for driving the same, of ways for said steps arranged so that the treads thereof form a stairway on the incline and a horizontal surface on the landings, a flexible 75 covering such as a mat for a portion of a landing, an alarm sounded each time the steps have advanced a distance equal to the width of one of the treads, an endless hand rail having alternate portions thereof the 80 length of the width of a tread of different appearance, and means for driving said hand rail in synchronism with the movement of the steps.

193. In a device of the class described, in 85 combination with the series of steps and means for driving the same, of ways for said steps arranged so that the treads thereof form a stairway on the incline and a horizontal surface on the landings, a guide pulley located adjacent to a landing, an endless hand rail running over said guide pulley in synchronism with the movement of the steps, a bell adjacent to said guide pulley, a hammer for said bell, and pins on said guide pulley 90 so spaced apart that the bell will be sounded every time the hand rail has advanced a distance equal to the width of the tread of the step.

194. In a device of the class described, the 100 combination with the series of steps and means for driving the same, of ways for said steps arranged so that the treads thereof form a stairway on the incline and a horizontal surface on the landings, an endless hand 105 rail moving in synchronism with said steps and substantially parallel to the path thereof, and means for indicating to the senses of touch and sight the synchronism of the movement of the steps and hand rail.

195. In a device of the class described, the combination with the series of steps and means for driving the same, of ways for said steps arranged so that the treads thereof form a stairway on the incline and a horizontal surface on the landings, an endless hand rail moving in synchronism with said steps and substantially parallel to the path thereof, and means for indicating to the senses of touch and hearing the synchronism of the 115 movement of the steps and hand rail.

196. In a device of the class described, the combination with the series of steps and means for driving the same, of ways for said steps arranged so that the treads thereof 125 form a stairway on the incline and a horizontal surface on the landings, an endless hand rail moving in synchronism with said steps and substantially parallel to the path thereof, and means for indicating to the 130

- senses of sight and hearing the synchronism of the movement of the steps and hand rail.
197. In a device of the class described, the combination with the series of steps and means for driving the same, of ways for said steps arranged so that the treads thereof form a stairway on the incline and a horizontal surface on the landings, an endless hand rail moving in synchronism with said steps and substantially parallel to the path thereof, and means for indicating to the senses of touch, sight and hearing the synchronism of the movement of the steps and hand rail.
198. In a conveying apparatus, a series of connected steps having risers, an inclined way on which the steps travel, a balustrade, and a curtain depending below the lower edge of the risers.
199. In a conveying apparatus, a series of connected steps having risers, an inclined way on which the steps travel, a balustrade, a curtain depending below the lower edge of the risers, and brackets carrying the curtain.
200. In a conveying apparatus, an inclined way, a series of connected steps having risers, wheels on the steps running on the way, a balustrade, and a curtain depending from the balustrade below the lower edge of the risers, the wheels being outside the curtain.
201. In a device of the class described, tracks having horizontal and inclined portions, steps traveling on the tracks, and balustrades at the ends of the steps having extension forming curtains extending below the tops of the steps.
202. In a device of the class described, the combination with the ways having a concave curve therein, of the steps adapted to move in said ways and having surfaces adapted to form horizontal landings and an inclined series of steps, and having their forward edges reduced so as to permit of their overlapping on said concave curve, and means for moving said steps.
203. In a device of the class described, the combination with the ways having a concave curve therein, of the steps adapted to move in said ways and having surfaces adapted to form horizontal landings and an inclined series of steps, links connecting said steps, said steps having their forward edges reduced so as to permit of their overlapping on said concave curve, and means for moving said steps with the ways.
204. In a device of the class described, the combination of runways disposed in inclined and horizontal planes, with a series of steps moving on the ways and forming stairs on the carrying portion of the incline and having their treads in substantial alignment on the return run.
205. In a device of the class described, an endless conveyer having oppositely moving inclined runs and a horizontal landing portion for the transporting run, and tracks for both runs, the tracks for the return run under the landing portion rising to a point substantially under the top of the transporting run.
206. In a device of the class described, an endless conveyer having oppositely moving upper and lower inclined runs, the upper run terminating in a horizontal landing portion, and a track circuit, the tracks for the lower run rising in a curve under the landing portion so as to provide a tangential portion or run on the return at the top of the incline.
207. In a device of the class described, an endless conveyer consisting of link connected steps providing oppositely moving upper and lower inclined runs, the upper run terminating in a horizontal landing portion, a track circuit, the tracks for the lower run rising in a curve under the landing portion to a point substantially under the top of the upper inclined run so as to narrow the throat of the machine, and a transverse shaft located at the throat and having pinions engaging the links of both runs.
208. In a device of the class described, upper and lower horizontal and inclined tracks, step sections arranged to travel on said tracks, a drive chain for driving said step sections, guides at each end of the stair-way for the step sections, and a transverse diaphragm between the upper and lower tracks.
209. In a device of the class described, the combination with a series of steps connected by a central driving chain, of upper and lower ways on which said steps travel, said ways including landing portions at different levels and an inclined portion connecting the same, and a transverse diaphragm between the upper and lower ways and located in the inclined and landing portions.
- In testimony whereof I affix my signature in presence of two witnesses.
- CHARLES D. SEEBERGER.
- Witnesses:
